UNITED STATES PATENT OFFICE.

ERNEST R. GODWARD, OF CHRISTCHURCH, NEW ZEALAND.

VAPORIZER FOR VOLATILE-FUEL MIXTURES.

Application filed February 27, 1923. Serial No. 621,517.

To all whom it may concern:

Be it known that I, ERNEST R. GODWARD, a subject of the King of Great Britain, residing at Christchurch, New Zealand, have invented certain new and useful Improvements in Vaporizers for Volatile-Fuel Mixtures; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in fuel vaporizers for use in connection with internal combustion engines, and for other uses; and, the invention has reference, more particularly, to a novel construction of vaporizing device which is allied in principle to that shown and described in my pending application for United States Letters Patent, filed August 26th, 1921, Serial No. 495,757.

This invention has for its principal object to provide a simple and inexpensive construction of vaporizer adapted to act upon an atomized liquid fuel mixture (such as is produced by the well known forms of atomizing carburetors) to reduce the same to a substantially uniform dry gaseous mixture prior to delivery thereof to the point of combustion. To this end the present invention provides a structure comprising a closed chamber having an intake conduit and a discharge conduit communicating with its upper end, a perpendicular liquid fuel supporting means of extensive surface area arranged below said intake and discharge conduits, the surface of which is provided by a plurality of vertically disposed partitions or walls spaced slightly apart, and a heat transfer means in engagement with the lower end of said fuel supporting means whereby heat is transferred to and conducted upwardly through said supporting means and consequently in a direction opposite to the natural gravitation of fuel lodged upon said supporting means, all whereby the heavier particles of liquid fuel may be deposited upon and within the supporting means to meet with increasing temperature as they gravitate upon the surface of the latter, so that said liquid particles may find a degree of heat adequate to vaporize the same where-

upon the fuel thus vaporized is returned out of the upper end of the supporting means to join and combine with the stream of fuel mixture passing out of the vaporizer through the discharge conduit.

The invention is clearly illustrated in the accompanying drawings, in which:—

Figure 1 is a vertical longitudinal section of the vaporizer device made according to and embodying the principles of this invention; Figure 2 is a transverse horizontal section, taken on line 2—2 in Figure 1; Figure 3 is a perspective view of a modified form of the fuel supporting means; Figure 4 is a similar perspective view of another modified form of the fuel supporting means; and Figure 5 is a fragmentary perspective of another modified form of said fuel supporting means.

Similar characters of reference are employed in all of the hereinabove described views, to indicate corresponding parts.

Referring now to said drawings, the reference character 6 indicates an outer casing, and 7 indicates a dome cover or closure connected with the upper end of said casing, the same terminating in a suitable discharge member or conduit 8. The lower or bottom end of said casing 6 is closed by a hot-plate 9, provided on its under side with depending heat conducting fingers or projections 10. Arranged beneath said hot-plate 9 and its projections 10 is a hot-box 11 providing a heat transfer chamber 12 into which said fingers or projections 10 extend. Leading into said hot-box 11 is a delivery pipe 13 through which a hot fluid may be introduced into said heat transfer chamber 12, such, for example, as the hot exhaust gases discharged from an internal combustion engine. Said dome cover or closure 7 is provided with a laterally projecting annular flange 14, and, in like manner, said hot-box 11 is also provided with a laterally projecting annular flange 15. Suitable bolts B are secured to and between the flanges 14 and 15 to secure the various above described elements together in operative assembled relation.

Arranged within the interior of said casing 6 so as to rest upon and engage said hot-plate 9, and so as to extend upwardly therefrom toward the top end of the casing, is the novel combined fuel supporting and heat conducting means, which comprises a plurality of vertical partition or plate sec-

2
tions 16 arranged one within the other and separated by intermediate perpendicular passages 17 open at their upper ends, but closed by said hot-plate 9 at their lower ends. Said partition or plate sections 16 and the intermediate passages 17 may be formed by rolling a sheet of metal upon itself in convolute form, as shown in Figures 1 and 2, or the same may be formed of a sheet of wire mesh or gauze 18 rolled in like manner in convolute form, as shown in Figure 3, or the same may be formed of perforate sheet metal 19 rolled in like manner in convolute form, as shown in Figure 5. It is also possible to form said fuel supporting and heat conducting means of tubular sections 20 of any of the desired above mentioned materials, said sections varying in diameter so as to nest together in suitably spaced apart relation adapted to provide the intermediate passages therebetween as illustrated more particularly in Figure 4 of the drawings.

The reference character 21 indicates a fuel mixture delivery member or conduit, which enters through the discharge means or conduit 8, and the inner end of which terminates in a bell mouth 22 spaced slightly above the upper end of said fuel supporting and heat conducting means, so as to provide a space 23 intermediate its mouth and said fuel supporting and heat conducting means affording direct communication with the discharge means or conduit 8. In the arrangement of intake or fuel mixture delivery member and outlet or discharge member shown in the drawings and above described, the former is smaller in diameter than the latter, and the same are concentrically related one to the other so as to dispose their respective conduits in parallel relation, with the resultant advantage that the incoming charge of atomized fuel mixture, which is cold, is by reason of its proximity to the warmed gas or vapor passing out through the discharge, enabled to absorb a certain amount of heat from the warm gas or vapor and thus cools the same prior to its delivery into the internal combustion engine served by the vaporizer, while at the same time the incoming fuel mixture is raised in temperature rendering the same more susceptible to vaporization. It will of course be understood that the illustrated and described concentric parallel arrangement of the intake and discharge conduits of the vaporizer, is only one specific form of the desired parallel arrangement, and that such parallel arrangement may be attained by mechanical modifications of the structure without departing from the scope of this invention in such respect.

It will be also understood that the heat transfer means constituted by the hot-box above described is subject to more or less

mechanical variation according to the character of the heat supplying medium which it may be desired to utilize.

The operation of the device in use, when e. g. it is connected intermediate a carburetor and the cylinders of an internal combustion engine, is as follows:—

The vaporizer interior and a carburetor are subjected to the effects of the suction strokes of the pistons in the engine cylinders through the discharge means or conduit 8 and the fuel mixture intake 21, so that petrol or other liquid combustible fuel is atomized with air in the carburetor to form a fuel mixture which is conducted through the intake 21 into the interior of the vaporizer above the fuel supporting and heat conducting means thereof. The more volatile portions or particles of the petrol are readily vaporized and combined with the air stream, so that the resultant combustible gas passes through the space 23 intermediate the mouth 22 of the intake 21 and is thence discharged to the engine cylinders through the discharge means or conduit 8. Since the admixture of atomized petrol with the air passing from the carburetor always contains a quantity of comparatively heavy liquid particles which are unvaporized, it is the object of this invention to provide a means whereby a substantially complete vaporization thereof is attained before passing into the engine cylinders. Such result is attained by means of the fuel supporting and heat conducting element of the vaporizer, the vertical walls and passages of which are disposed below the mouth 22 of the intake 21 in substantial alinement with the direction of movement of the fuel mixture through the intake 21 and into the vaporizer. When the mixture of air and fuel turns upwardly and outwardly through the discharge means 8, said heavier particles of liquid petrol tend to continue their movement in a downward direction, and the same are consequently thrown, as it were, into the passages 17 and upon the surfaces of the walls 16, and thereupon tend to creep downward or gravitate toward the hot-plate 9. Since the walls 16 are engaged by their lower ends directly with said hot-plate 9, the heat of the latter is communicated thereto, and is conducted upwardly therethrough, or in other words the conducted heat travels in the opposite direction to the gravitation of the liquid petrol particles. As a result of this action the gravitating particles of petrol are constantly spreading out and moving toward points of increasing temperature, with the consequence that the liquid particles are quickly vaporized as soon as they meet with a temperature adequate to produce such effect. The fuel vapor thus produced fills the passages 17 and escapes out of the open upper ends of the same, whereupon the escaping va- 120 125 130 135 140 145 150 155 160 165 170 175 180 185 190 195 200

por returns to and combines with the moving stream of fuel mixture which is being discharged through the conduit 8 to the engine cylinders.

5 Having thus described the construction and mode of operation of my present invention, I claim:—

1. A vaporizer for volatile fuel mixtures or the like comprising a casing having a 10 heat transfer means at its lower end, a fuel supporting and heat conducting means within said casing comprising a plurality of laterally spaced apart vertical walls defining intermediate passages, said walls being 15 disposed so that their lower ends are in heat receiving engagement with and the lower end of the passages defined thereby closed by said heat transfer means, and fuel mixture intake and discharge means 20 communicating with the upper end of said casing and so arranged as to pass a moving stream of fuel mixture above and across the open upper ends of said passages intermediate said walls for the purposes de- 25 scribed.

2. A vaporizer for volatile fuel mixtures or the like comprising a casing, a transverse partition providing a hot-plate dividing the interior of said casing to provide a heat 30 transfer chamber at the bottom thereof, means for introducing a heating medium into said heat transfer chamber, a fuel sup- porting and heat conducting means within said casing comprising a plurality of lat- 35 erally spaced apart vertical walls defining intermediate passages, said walls being dis- posed so that their lower ends are in heat re- ceiving engagement with and the lower end of the passages defined thereby and closed

by said hot-plate, and fuel mixture intake 40 and discharge means communicating with the upper end of said casing and so ar- ranged as to pass a moving stream of fuel mixture above and across the open upper ends of said passages intermediate said walls 45 for the purposes described.

3. A vaporizer for volatile fuel mixtures or the like comprising a casing having a 50 heat transfer means at its lower end, a fuel supporting and heat conducting means within said casing having its lower end in heat receiving contact with and closed by said heat transfer means, and fuel mixture in- take and discharge means communicating 55 with the upper end of said casing and so arranged as to pass a moving stream of fuel mixture above and across the open upper end of said fuel supporting and heat con- ducting means, said fuel mixture intake and discharge means being disposed in intimate 60 parallel relation for the purposes described.

4. A vaporizer as characterized in claim 1 in which the ducts of said fuel mixture and discharge means are disposed in inti- 65 mate parallel relation for the purposes de- scribed.

5. A vaporizer as characterized in claim 2 in which the ducts of said fuel mixture and discharge means are disposed in inti- 70 mate parallel relation for the purposes de- scribed.

In testimony that I claim the invention set forth above I have hereunto set my hand this 14th day of February, 1923.

ERNEST R. GODWARD.
